UNITED STATES PATENT OFFICE.

RALPH M. COEN, OF NEW YORK, N. Y.

TOILET-KIT HOLDER.

1,281,296.

Specification of Letters Patent. Patented Oct. 15, 1918.

Application filed April 6, 1918. Serial No. 227,046.

To all whom it may concern:

Be it known that I, RALPH M. COEN, a citizen of the United States, and a resident of the borough of Manhattan, city, county and State of New York, have invented certain new and useful Improvements in Toilet-Kit Holders, of which the following is a specification.

My improvements relate to flexible and foldable holders for the storage and transportation of "kits" of various kinds, more especially for travelers' toilet kits. The object of the invention is to afford simple but effective means whereby the several articles may be securely held in position in the holder, at the same time strengthening and reinforcing the latter and maintaining its shape, all as hereinafter fully set forth and claimed specifically,—a distinctive feature being the use of transverse base plates which not only stiffen the holder laterally, but also act as foundations for the male or button stud members of the fastenings used to pinch the retaining straps, and at the same time afford a rigid support for the bights of said retaining straps when folded thereunder, thereby effectually locking the straps and articles embraced thereby.

In the accompanying drawings, Figure 1, is a view of my improved kit holder opened up and spread out ready for the positioning of toilet articles;

Fig. 2, is a longitudinal section taken upon planes of line 2—2, Fig. 1;

Fig. 3, is a view similar to Fig. 1, but showing toilet articles secured in position;

Fig. 4, is a sectional detail, full size, showing a cross section of one of the base plates and its relation to the inturned end and bight of a retaining strap;

Fig. 5, is a sectional detail of a base plate and fastenings.

As before intimated the present invention relates more particularly to the means for securing the outer or free ends of the straps *s*, *s*, which are used to retain the toilet or other articles *a*, in position in the holder *H*, considering the latter as a whole. Thus *h*, represents the back or outer covering of the holder, which is formed with body pockets *h'*, *h'*, and an end flap pocket *h*². *h*³ are the side flaps, which fold over the body pockets *h'*, *h'*, and cover the articles *a*, held by the retaining straps *s*, as indicated in Fig. 3.

The retaining straps *s*, *s*, are secured at one

end to the body of the holder *H*, and are of such length that their free ends may be tucked into the body pockets *h'*, *h'*. *b*, *b*, are cross-bands attached to the inner facings 60 of the pockets *h'*, *h'*, in alinement with the longitudinal extensions of the retaining straps *s*, *s*, which are passed under these cross bands *b*, *b*, as shown particularly in Fig. 3,— the cross bands *b*, enabling the retaining 65 straps to be formed into loops *s'*, *s'*, to embrace any of the articles *a*, desired,—the loops *s'*, *s'*, being larger or smaller according to the sizes and character of the articles *a*, to be accommodated.

In the back *h*, of the holder *H*, are incorporated elongated base plates *p*, preferably of metal,—these base plates *p*, being positioned parallel to and coincident with the edges of the body pockets *h'*, *h'*. Extending laterally across the back *h*, of the holder *H*, the base plates *b* act as ribs to reinforce and maintain the shape of the body of the holder. They also perform the more important functions of relatively rigid supports for the male or button members *m'*, of the socket fastenings *m*, by which the mouths of the body pockets *h'*, are secured in closed position, and of pressure plates to hold the inturned ends of the retaining straps *s*, 85 firmly in position, as shown more particularly in Fig. 4, of the drawings, by reference to which it will be seen that the parts of the strap *s*, adjacent to the bight *s'*, are pinched between the cross band *b*, and the base plate *p*. Thus when the edges of the pockets *h'*, are secured by the fastenings *m*, to the base plates adjacent to the retaining straps *s*, the latter will be firmly locked against longitudinal movement or slip, 90 thereby holding the embraced articles *a*, firmly in position.

The portions of the back *h*, between the pockets form flexible ligaments which admit of the folding of the holder upon itself in 100 the usual way. *c*, is an exterior strap and *c'*, a buckle by which the holder may be held in folded relationship.

The base plates *p*, are an important factor in strengthening and maintaining the shape 105 of the holder against lateral collapse or compression, but their more important function is the locking of the inturned ends of the retaining straps *s*, *s*, as herein set forth.

What I claim as my invention and desire 110 to secure by Letters Patent is,

1. In a kit holder of the character desig-

nated, the combination of a backing formed with a body pocket, cross bands on the face of the pocket, a retaining strap secured to the holder and adapted to be passed under 5 said cross bands and be tucked into the pocket, a base plate on the back of the holder in alinement with the edge of the pocket, and means for positively securing said edge of the pocket to the base plate, for 10 the purpose described.

2. In a kit holder of the character designated, the combination of a backing formed with body pockets, cross bands on the faces of the pockets, retaining straps 15 secured to the holder and adapted to be passed under said cross bands and to be tucked into said pockets, base plates on the back of the holder in alinement with the edges of the pockets, and means for positively securing the edges of said pockets to 20 the base plates, for the purpose described.

3. In a kit holder of the character designated, the combination of a backing formed with body pockets, cross bands on 25 the faces of the pockets, retaining straps secured to the holder and adapted to be passed under said cross bands and to be tucked into

said pockets, base plates on the back of the holder in alinement with the edges of the pockets, and means for positively securing 30 the edges of said pockets to the base plate, said means consisting of male button members rigidly attached to the base plates, and of engaging socket pieces on the edges of the pockets, for the purpose described. 35

4. In a kit holder of the character designated, the combination of a backing with pockets, a base plate, a retaining strap adapted to have its end tucked in one of 40 said pockets, and a positive lock for said strap.

5. In a kit holder of the character designated, the combination of a backing with pockets, a base plate, a retaining strap adapted to have its end tucked in one of 45 said pockets, and a positive lock for said strap, said base plate extending at right angles to the length of the strap and serving to hold the holder against lateral collapse and to lock the inturned end of the strap.

RALPH M. COEN.
